HUBERT ELWELL SMITH, OF EDINBURGH, SCOTLAND.

CARBURETING APPARATUS.

No. 883,249.

Specification of Letters Patent. Patented March 31, 1908

Application filed March 18, 1907. Serial No. 362,974.

To all whom it may concern:

Be it known that I, HUBERT ELWELL SMITH, electrical engineer, a subject of the King of Great Britain, residing at 52 Frederick street, in the city of Edinburgh, Scotland, have invented new and useful Improvements in and Relating to Carbureting Apparatus, of which the following is a specification:

10 This invention relates to an apparatus designed for the carbureting of air and consists in improved arrangements whereby the vaporization of the petrol or other hydrocarbon employed is facilitated.

15 In order that the hydrocarbon may be easily vaporized it is desirable that it should be spread out in the form of a thin layer over which the air to be carbureted is caused to pass. It has been found that various difficulties have been met with in practice in the use of such carbureting apparatus. In particular where the carbureter is intended to work without heating there is a difficulty in that the rapid vaporization of the hydrocarbon causes the liquid to freeze when the vaporization immediately ceases almost completely. Another difficulty arises from the fact that the vaporization proceeds more easily at high than at low temperatures so 20 that should there be any difference in temperature between different parts of the carbureter the carbureted air obtained from the apparatus would not be constant in composition but in some parts will be too rich in 25 hydrocarbon and in other parts too poor.

According to the present invention a construction is employed by which the petrol is spread out over sloping surfaces which radiate from a point as for example conical or 30 pyramidal surfaces: When extended into a sufficiently thin film the petrol may be allowed to flow vertically downward but if the speed should be too great it may be checked by suitably shaping the surface over which it 35 flows. To secure an even temperature the whole carbureter may be immersed in water or in some anti-freezing liquid and the effect of this water or liquid jacket is accentuated by providing stirring apparatus which prevents any difference of temperature arising 40 between one part of the apparatus and another.

The invention is illustrated in the accompanying drawings in which—

45 Figure 1 shows one form of carbureter designed in accordance with this invention.

Fig. 2 is an enlarged detail of the stirring apparatus thereof. Fig. 3 shows a modified form of carbureter, and Fig. 4 a corresponding enlarged view of a modified stirring apparatus. Fig. 5 shows yet another modification of the stirring apparatus.

In Fig. 1 *a* is the containing vessel or chamber which incloses and protects the carbureter. Within this vessel is arranged the carbureter proper which consists of an outer casing *b* comprising a series of chambers made out of thin sheet metal or the like and taking the shape of cones or truncated cones put base to base or arranged above and below a cylindrical portion. Thus it will be seen that in Fig. 1 the uppermost chamber consists of two truncated cones put base to base while the lower chambers have a middle cylindrical portion. Within the outer casing *b* is a second casing *c* similar in shape so that between the two casings is left a space of considerable area but small depth. This inner casing *c* is hollow and both it and the outer chamber *a* are adapted to be filled with water or other liquid up to the level indicated.

The space between the casings *b* and *c* is open at the top to the air space which is included in the air-tight chamber *a* above the liquid. Air is supplied by the pipe *d* to this space and passes into the carbureting chamber at *e*. A plate or the like *13* is provided between the air-pipe and the water seal to prevent excessive vaporization of the water and consequent moistening of the air. The petrol is supplied by one or more pipes *f* from a suitable apparatus which should preferably exactly proportion the quantity of petrol supplied to the quantity of air passing. The vertical pipes *f* terminate in a horizontal circular pipe *g* which has in it a number of mounted perforations through which the petrol is uniformly distributed over the surface of the first cone of the casing *c*. In the center of the casing *c* is arranged a vertical rod *h*, to which are attached slanting plates or blades *k*. The rod *h* is squared at its lower end as shown at *l*. The rod is adapted to be reciprocated in a vertical direction by levers operated from the air pump of the apparatus or in any suitable fashion. In order to produce a constant stirring in one direction the rod is so arranged that in rising it cannot turn and movement of the blades, therefore, pushes the liquid sidewise. In

105 descending, however, the rod can turn and consequently the blades *k* do not displace the

liquid appreciably at all. Thus the liquid is continually propelled in one direction only instead of being alternately pushed backward and forward as it would be if the rod could never rotate. The arrangement for effecting this movement of the rod is illustrated in more detail in Fig. 2. A bracket *m* is provided within which a circular nut *n* fitting over the square end *l* of the rod *h* rotates. The nut *n* is prevented from rising or falling out of its place by means of one or more screws *p* which pass through the bracket *m* into a slot *q* in the nut *n*. Upon the bracket *m* are arranged wedge shaped projections *r* and on the nut *n* is a pivoted projection *s* which is adapted to engage with the vertical sides of the projections *r* in one direction and so prevent the turning of the rod *h*, while in the other direction the projection *s* rides up the sliding sides of the projections *r*. The carbureted air yielded by the carbureter is removed by the pipe *t*. It has been found that the vertical portion of the path of the hydrocarbon is the most valuable in the production of vapor, the only drawback being the speed at which the hydrocarbon travels. The carbureter, therefore, may be modified to take the form shown in Fig. 3. Here the containing vessel *a* remains as before. The outer casing *b* becomes now a simple cylinder or slightly tapering cone *v* while the inner casing *c* becomes also a cylinder *w* or is made slightly conical but retains the conical or pyramidal top *x* which is necessary for the distribution of the petrol. The space within the casing *w* and also that between the casings *v* and vessel *a* may be filled as before with liquid. The petrol is admitted by the pipes *f* and is distributed over the surface of the cone *x* or pyramid *x* by means of a vertical ring or collar *y* which rests upon the cone and has its lower edge divided into saw teeth through gaps between which the petrol slowly runs. It will be seen that in this form of carbureter there is a large extent of vertical or nearly vertical surface provided for the petrol to flow over when once it has been spread out into a sufficiently thin layer by the cone *x*. Air enters by the pipe *d* as before and a combustible gas leaves by the pipe *t*. Stirrers *k* are again provided on the vertical rod *h* in the middle of the inner casing *w* but a modified form of operating mechanism is shown for this rod. This mechanism appears more in detail in Fig. 4 where it will be seen that on the top of the rod *h* is mounted a bevel wheel *z*, so that it can rotate freely upon the end of the rod. This bevel wheel *z* gears with bevel teeth on a vertical quadrant *5* which is pivoted at 2 and operated by links 3, 4 from some moving part of the air pump of the carbureting apparatus or by any prime motor. The sleeve attached to the bevel wheel *z* has on it a pivoted pawl *6* which moves over a

ratchet 7 formed on the top of the bracket *8* which surrounds the rod *h* and is attached thereto by means of a screw 9 or the like so that it rotates with the rod. It will be seen that with this arrangement the movement of the quadrant 5 in one direction rotates the bevel wheel *z* without moving the rod *h* because the pawl 6 moves freely over the ratchet 7. In the other direction, however, the pawl engages with the ratchet and so turns the bracket 8 and through it the rod *h*. By this means a uniform stirring in one direction is obtained just as by the arrangement shown in Figs. 1 and 2.

An alternative stirring apparatus is illustrated by Fig. 5 which shows a vertical rod *h* which is here square in section with two of the blades *k*. These blades are supported one on either side upon the rod *h* by wings 10, pivoted to the rod by pins 11. A second pin 12 projects from each wing and is adapted to come in contact with the rod *h*. The blade *k* is free to move about the pivot 11 either upward or downward but its movement in each direction is limited upwardly by the edge of the blade striking the rod *h* and downwardly by the pin 12 striking the rod. When this form of apparatus is used the rod *h* is simply reciprocated vertically. During the upward movement the blades *k* will assume their lower position sloping downwards and consequently the liquid will tend to be forced round the container. In the downward movement the blades *k* will assume the upper position but again the liquid will be forced in the same direction round the container. In this way as before a continuous circulation of liquid will be maintained, the liquid passing forward from the blades in a circular direction around the central space.

It will be clear that either form of stirring device may be used with either form of carbureter. Moreover the construction of the carbureter is not precisely limited to the two forms shown since modifications of these forms can easily be made. Fig. 1 for example is intended to suggest that a carbureter might be made of a series of simple conical chambers like the uppermost chamber in that figure or of course all the chambers might be like the lower one shown. The form of carbureter shown in Fig. 3 is simply derived from that in Fig. 1 by enlarging the cylindrical part of the chambers. As above mentioned the only disadvantage of this form is that the petrol tends to flow rather too quickly down the vertical path. To hinder this the cylindrical side of the casing *w* may be corrugated or may be covered with gauze soldered to it, or by suitable means the surfaces may be roughened by a small projection upon it. Any such device as this will suffice to slightly check the rate of flow of petrol and so aid in the efficient vaporization. A drain cock may be provided in the

bottom of the carbureting chamber as indicated at 13 in Fig. 3 in case of accidental flooding from any cause, for ordinarily it will be found that the hydrocarbon is so completely vaporized that there is no accumulation of it. It will be obvious that many modifications may be made in the various details of the apparatus, while yet maintaining the principle of the invention.

10. What I claim is:—

1. In carbureting apparatus the combination of an inner casing having upper surfaces sloping down from a center in such manner as to be adapted to spread out a hydrocarbon, with an outer casing inclosing and closely fitting said inner casing so as to leave a narrow space between the two, hydrocarbon and air supply pipes and an exit pipe.

2. In carbureting apparatus the combination of an inner casing having surfaces at first sloping down from a center in such manner as to be adapted to spread out a hydrocarbon and afterwards nearly vertical, with an outer casing closely fitting said inner casing, but leaving a narrow space between the two, hydrocarbon and air supply pipes and an exit pipe.

3. In carbureting apparatus the combination of an inner casing having upper surfaces sloping down from a center in such manner as to be adapted to spread out a hydrocarbon, with an outer casing inclosing and closely fitting said inner casing so as to leave a narrow space between the two, means for distributing the hydrocarbon about the center of said upper surfaces, hydrocarbon and air supply pipes and an exit pipe.

4. In carbureting apparatus the combination of an inner casing having upper surfaces sloping down from a center in such a manner as to be adapted to spread out a hydrocarbon, with an outer casing inclosing and closely fitting said inner casing so as to leave a narrow space between the two, hydrocarbon supply pipes terminating in a perforated channel surrounding the center of said upper surfaces, an air supply pipe and an exit pipe.

5. In carbureting apparatus the combina-

tion of an inner casing having upper surfaces sloping down from a center and adapted to spread out a hydrocarbon with an outer casing closely fitting said inner casing so as to leave a narrow space between the two, hydrocarbon and air supply pipes, an exit pipe, a containing vessel surrounding said casings and adapted to hold liquid which is in contact with both casings, and means for stirring said liquid, said means comprising a vertical rod passing through the center of the inner casing and carrying blades, with mechanism for causing the movement of said blades.

6. In carbureting apparatus the combination of an inner casing having upper surfaces sloping down from a center and adapted to spread out a hydrocarbon, with an outer casing closely fitting said inner casing so as to leave a narrow space between the two, hydrocarbon and air supply pipes, an exit pipe, a containing vessel surrounding said casings and adapted to hold liquid which is in contact with both casings, and means for stirring said liquid, said means comprising a vertical rod passing through the center of the inner casing, mechanism for causing the reciprocation of said rod, and blades attached to said rod so as to move relatively to it upon reversal of the motion of the rod.

7. In carbureting apparatus the combination of an inner casing having upper surfaces sloping down from a center and adapted to spread out a hydrocarbon with an outer casing closely fitting said inner casing so as to leave a narrow space between the two, a containing vessel surrounding said casings and adapted to be filled with liquid, hydrocarbon and air supply pipes, a shield to prevent evaporation of the water and an exit pipe.
